UNITED STATES PATENT OFFICE.

JOHN OWEN DAVIS, OF CUSHING, OKLAHOMA.

RAILROAD-TIE.

1,312,020.

Specification of Letters Patent.

Patented Aug. 5, 1919.

Application filed May 1, 1919. Serial No. 293,932.

To all whom it may concern:

Be it known that I, JOHN OWEN DAVIS, a citizen of the United States, and a resident of Cushing, in the county of Payne and 5 State of Oklahoma, have invented certain new and useful Improvements in Railroad-Ties, of which the following is a specification.

My present invention relates generally to 10 railroad ties, and more particularly to composite ties, my object being the provision of a tie formed of structural steel and concrete, so arranged as to provide for the ready introduction of the plastic material in connection with the metal, without the necessity 15 for forms, molds, and the like.

A further object is the provision of a 20 metal and concrete tie, the parts of which are so arranged as to provide for the reception and ready securing of cushion blocks upon the rail seats.

Further objects, and the particular advantages of my present construction, will be apparent from the following description, 25 reference being made to the accompanying drawings forming a part of the specification, in which:—

Figure 1 is a perspective view of my improved tie complete,

Fig. 2 is a vertical longitudinal section 30 taken through one end thereof on an enlarged scale, and

Fig. 3 is a transverse vertical section taken 35 through one end of the tie seen in Fig. 2.

Referring now to these figures, and particularly to Fig. 1, my invention proposes a tie including a metal shell, having sides 10 and 11 which extend from one end to the other and form a rigid structure, the opposite 40 ends of the shell being so formed as to provide downwardly opening hopper-like end portions generally indicated at 12 and 13, and of which the end portions of the sides 10 and 11 constitute parts.

It may be possible to form these hopper-like 45 end portions of the tie by pressing sheet metal, or they may be made up by outer and inner upwardly and inwardly inclined plates 14 and 15 at each end, both these outer and 50 inner plates 14 and 15 being riveted or otherwise connected, as at 16, to the sides 10 and 11.

In the arrangement as shown, the upper 55 inner edges of the inclined plates 14 and 15 thus coöperate to define the rail seats at the opposite ends of the tie, although the sides

10 and 11, as shown, are provided with upper upright flanges 17 which project at their ends above the upper edges of the inclined plates 14 and 15, so as to extend along opposite sides of cushion blocks 18, the latter of which are preferably formed of wood and seat upon the upper edges of plates 14 and 15, as well as the upper surface of the plastic material within the hopper-like end portions of the rail, as presently described.

These cushion blocks 18 thus serve to cushion the rails in use, as well as a means of receiving the usual spikes 19 for holding the rails in place, and these cushion blocks 70 18 are preferably covered by upper horizontally disposed metal plates 20 having openings 21, as seen at the right of Fig. 1, and in spaced relation, through which the spikes 19 are driven.

Thus, with the metallic shell formed and the cushion blocks 18 disposed in place, the latter of which are secured by transverse bolts 22, projecting at their ends through the end portions of the upright flanges 17 of the 80 sides 10 and 11, the tie may be conveniently reversed and the plastic material 23 poured into the hopper-like end portions thereof, and the operation, except for the drying of the plastic material, is finished by merely 85 scraping the surplus plastic material away by passing any form of straight edge along the lower edges of the plates 14 and 15 and the end portions of the sides 10 and 11.

The plastic material 23 is preferably reinforced by series of crimped spikes 24, extending transversely therein through the end portions of the opposite sides 10 and 11 and as shown particularly in Fig. 3.

It will be noted that my invention thus 95 provides a rail tie in connection with which all of the advantages of a wooden tie are present, as the spaced sides 10 and 11 between the hopper-like end portions where the rail seats are located, is entirely open 100 for the reception of the road ballast, so as to obviate the possibility of difficulty in the way of center binding.

It is also obvious that my invention proposes a tie in which the plastic filled portions of the metallic shell may be completed 105 without the use of molds, forms, and the like, which in ordinary practice means considerable expense in both labor and material.

It is also to be observed in my particular 110 construction of tie that the concrete is reinforced from without and entirely protected

from injury when the tie is placed in use, the two spaced and composite rail seats being rigidly connected by the side members which stand on edge so that all danger of splitting of the end portion of the tie is entirely prevented and all danger of splitting the rails avoided.

It will also be noted that the sides 10 and 11 are provided with openings 10^a for the convenience of workmen in handling the ties, suitable hooks being inserted in these openings for carrying the ties from place to place, and shifting the same into proper position, after which ballast of suitable description is filled into the open space within the shell and between the rail seats, which with the ballast between the ties, serves to effectively anchor the tie to the road-bed and maintain the rails in perfect alinement. It is to be observed furthermore that the foregoing is true particularly in view of the inverted hopper shaped bases of the rail seats which provide for a large bearing surface so that a smaller number of ties will be required per mile than the usual wooden ties. The tie proposed by my invention is in the nature of a much more permanent construction than usual, and obviously does away with the necessity of frequently tearing up the road-bed in the case of necessary substitution of wooden ties.

I claim:—

1. A rail tie consisting of a metallic shell formed with downwardly opening hopper-shaped end portions, and a plastic reinforcement within the said hopper-like end portions to coöperate with the shell in forming end seats at the ends thereof.

2. A rail tie consisting of a metallic shell formed with downwardly opening hopper-shaped end portions and having spaced apart sides rigidly connecting the said end portions, and plastic material within the said hopper-like end portions as and for the purpose described.

3. A rail tie consisting of a metallic shell formed with downwardly opening hopper-shaped end portions and having sides, the ends of which form parts of the said end portions of the tie, and which extend endwise in a vertical plane between the end portions of the tie, and a plastic material within the hopper-like end portions, as and for the purpose described.

4. A rail tie consisting of a shell having hopper-like end portions and side walls extending between and rigidly connected to said end portions, plastic material within and filling the hopper-like end portions, and reinforcing members extending into the said plastic material through the end portions of the said side walls.

5. A rail tie consisting of a shell having hopper-like end portions and having side walls connected to said end portions and

provided with upper flanges extending above the end portions, plastic material filling the said hopper-like end portions, to form rail seats at the opposite ends of the tie, and spike-receiving cushion blocks disposed on the said rail seats and secured to the upwardly extending portions of the said sides.

6. A rail tie consisting of a metallic shell having spaced parallel side walls and hopper-like end portions of which the end portions of the said side walls form the sides, said hopper-like end portions having opposing inclined walls extending between and connected to the side walls and flush with one another at their upper edges, the said side walls being provided with upper flanges projecting above the upper edges of the said inner and outer walls of the end portions of the tie, cushion blocks disposed between the said upright portions of the side walls above the hopper-like end portions, and connected to the said portions of the side walls, and plastic material filling the hopper-like end portions of the tie and coöperating with the upper edges of the said inclined walls to form solid seats for the said cushion blocks.

7. A rail tie having longitudinally spaced hopper-like end portions the sides of which are extended in unbroken relation between the said hopper-like end portions and in spaced parallel relation to one another, each of said hopper-like end portions having inner and outer inclined walls between the said side walls and having upper and lower edges terminating flush with one another, the said side walls having upright portions projecting above the upper edges of the inner and outer walls, cushion blocks disposed upon the upper edges of the inner and outer walls, bolts extending through said cushion blocks and through the upwardly projecting portions of the side walls, and a plastic filling within each of the hopper-like end portions, coöperating with the upper edges of the inner and outer walls to form solid seats for the said cushion blocks.

8. A rail tie having longitudinally spaced hopper-like end portions the sides of which are extended in unbroken relation between the said hopper-like end portions and in spaced parallel relation to one another, each of said hopper-like end portions having inner and outer inclined walls between the said side walls and having upper and lower edges terminating flush with one another, the said side walls having upright portions projecting above the upper edges of the inner and outer walls, cushion blocks disposed upon the upper edges of the inner and outer walls, bolts extending through said cushion blocks and through the upwardly projecting portions of the side walls, a plastic filling

within each of the hopper-like end portions, coöperating with the upper edges of the inner and outer walls to form solid seats for the said cushion blocks, and reinforcing members for the plastic material in the form of crimped spikes extending therein through the end portions of the said side walls.

9. A rail tie having longitudinally spaced hopper-like end portions the sides of which are extended in unbroken relation between the said hopper-like end portions and in spaced parallel relation to one another, each of said hopper-like end portions having inner and outer inclined walls between the said side walls and having upper and lower edges terminating flush with one another, the said side walls having upright portions projecting above the upper edges of the

inner and outer walls, cushion blocks disposed upon the upper edges of the inner and outer walls, bolts extending through said cushion blocks and through the upwardly projecting portions of the side walls, a plastic filling within each of the hopper-like end portions, coöperating with the upper edges of the inner and outer walls to form solid seats for the said cushion blocks, and protecting plates disposed upon the upper surfaces of the said cushion blocks and having spike-receiving apertures, as described.
